CLAIM

The ornamental design for a car air diffuser, as shown and described.

DESCRIPTION

FIG. 1 is a perspective view of an air diffuser showing a new design;

FIG. 2 is a front view of the air diffuser of FIG. 1;

FIG. 3 is a rear view of the air diffuser of FIG. 1;

FIG. 4 is a left side view of the air diffuser of FIG. 1;

FIG. 5 is a right side view of the air diffuser of FIG. 1;

FIG. 6 is a bottom view of the air diffuser of FIG. 1 showing the diffuser in an open position;

FIG. 7 is a top view of the air diffuser of FIG. 1; and,

FIG. 8 is a bottom view of the air diffuser of FIG. 1 showing the diffuser in a closed position.

The broken lines shown in FIGS. 1 and 3-8 are for the purpose of illustrating environmental structure and form no part of the claimed design.
